UNITED STATES PATENT OFFICE.

CLAUDE CHAPMAN FARWELL, OF GROTON, MASSACHUSETTS.

SHUTTLE-THROWING DEVICE.

Application filed July 20, 1926. Serial No. 123,740.

This invention relates to shuttle throwing devices and has for an object to provide an electrically operated construction wherein the parts are so made that the shock of 5 the loom will be readily taken up.

Another object of the invention is to provide a solenoid actuated core and associated parts for throwing a shuttle, the structure being such that the rapid motion of the 10 core is checked at a desired time and the blow cushioned.

Another object of the invention is to provide in an electrically operated shuttle throwing mechanism means for normally 15 using a binder in connection with a shuttle and a magnet for moving the binder out of functioning position.

An additional object is to provide in an electrically operated shuttle throwing device 20 means for turning off the current whenever the loom is stopped and for automatically turning on the current when the loom is started.

In the accompanying drawings—

25 Figure 1 is a diagram with certain parts in elevation and certain in section disclosing an embodiment of the invention.

Figure 2 is an enlarged vertical sectional view through part of a lay, the solenoid and 30 associated parts illustrating certain features of the invention.

Figure 3 is a top plan view of the structure shown in Figure 2.

Figure 4 is a sectional view through Figure 2 on line 4—4.

Figure 5 is a fragmentary longitudinal sectional view through a loom showing the lay and certain associated parts.

Referring to the accompanying drawings 40 by numerals, 1 indicates the frame of a loom and 2 the lay which is of usual construction and operated in the usual manner. In the accompanying drawings the invention has been applied to the under surface of 45 the lay 2 but under some circumstances, as for instance, with box looms, the solenoid and certain other parts would be placed on the side of the lay. As indicated in Figure 1, there is provided solenoids 3 and 4 arranged adjacent the respective ends of the lay 2 so as to throw the shuttle back and forth as the loom operates. As these are of identical construction, the description of one 50 will apply to both.

55 In Figures 2 to 4 inclusive, the solenoid 3 and associated parts have been shown in

detail. Referring to these figures it will be noted that the solenoid 3 is provided with an iron casing 5 making the solenoid what is known as an iron clad solenoid. In order 60 to assist the return of the flux, a short core 6 is provided and extends a short distance into one end of the solenoid and is held in position by a spring 7. The power core 8 is adapted to be drawn into the solenoid and checked in its movement by the core 6 and spring 7. It will be noted that core 6 helps complete the path for the flux whereby the core 8 may more quickly move and at the 65 same time the spring 7 acts to cushion and slow down the motion of the core 8. Suitable guides 9 are connected with the core 8 in any desired manner, said guides acting to guide the power core 8 in its reciproca- 70 tory motion and also acting to guide the arm 10 secured substantially centrally to the core 8 extending in one direction through a suitable slot 11 in lay 2 and in the opposite direction to a point where it is secured 75 to the rod 12. Rod 12 is guided by the bracket 13 and is surrounded by a spring 14 which acts to normally return the parts 80 to the position shown in Figure 2. Arm 10 is provided with a striking end 15 adapted to engage and strike the end of the shuttle 16 for throwing the same. The shuttle 16 is normally held against movement by the binder 17 which is a flat metal spring connected at 18 to an upstanding flange or plate 19 connected with the lay 2. As the 85 binder or spring 17 is free at one end it will yield as the shuttle 16 moves into engagement with the head 15 and will act to clamp or bind the shuttle in this position. In order 90 to relieve this clamping or binding action at the time that the arm 10 functions for throwing the shuttle, the electromagnet 20 is energized and pulls the binder 17 away from the shuttle thus releasing the same for 95 easy throwing. It is understood that the amount of movement of the binder 17 is 100 small but is sufficient to remove the pressure thereof against the shuttle.

In Figure 1, a diagram is shown illustrating how the winding of the core 3 and the winding of magnet 20 is connected to a source of current and how the current is turned on and off to the respective solenoids and magnets. At the right of Figure 1 will be seen a section 1' forming part 105 of the frame 1 and this section carries insulating supports 21 and 22 which are of 110

identical construction except that one is associated with solenoid 3 and the other with solenoid 4. In view of this fact the description of one will apply to both. Member 21 is provided with movable contacts 23 and 24 normally held apart by the spring 25 acting on the stop 25' rigidly secured to contact 24. Contact 24 at the outer end is provided with a rounded knob 26 insulated from the contact 24 and normally in the path of movement of the projection or cam 27 carried by the gear wheel 28. Contact 23 is normally held in the position shown in Figure 1 by a spring 29, said spring acting against the stop 30 rigidly secured to the contact 23. The gear wheel 28 continually meshes with the pinion 31 rigidly secured to the shaft 32, which shaft drives the lay 2 whereby the cam 27 is properly timed for closing the circuit at point 33 and also at point 34. When the circuit is closed at point 33, current will flow from the source 35 through wire 36, switch 37, wire 38, wire 39, magnet 20, wire 40, solenoid 3, wire 41, contact 23, contact 24, wire 42 and through wire 43 back to the source. The switch 37 is associated with a shipper handle 44 which is used for starting and stopping the loom. When the shipper handle 44 is in the position shown in Figure 1, the loom has been stopped and power drawn off. When it is desired to throw the power on and start the loom, shipper handle 44 is moved to the left in Figure 1 until it is almost vertical. This will start the loom and at the same time the contact 37' will be moved over for closing the switch 37. When the shipper handle 44 is moved for stopping the loom, the spring 37' will move contact 37' so as to open the switch 37 automatically. When the cam 27 engages the knob 26', the circuit will be closed for solenoid 4 and its co-acting magnet 20'. It will be understood that as the gear wheel 28 rotates, the knobs 26 and 26' will be alternately engaged and the contacts associated therewith caused to alternately function whereby the shuttle will be thrown back and forth in the usual manner.

What I claim is:

- 50 1. A shuttle throwing device including a solenoid, a core adapted to be attracted by the solenoid, means for retracting said core, an arm connected with the core for engaging and throwing a shuttle, a binder for normally holding the shuttle against movement until said arm functions and an electromagnetic member acting on said binder for pulling the same away from the shuttle substantially at the same time as said arm starts to function.
- 55 2. A shuttle throwing device including a

solenoid, a core adapted to be attracted by the solenoid, means acting as an iron shell for the solenoid, an auxiliary core arranged at one end of the solenoid, a spring for resiliently holding the auxiliary core in the 65 solenoid whereby when the first mentioned core is attracted by the solenoid it will strike the auxiliary core and move the same against the action of said spring, an arm connected with said core for actuating a shuttle, and 70 means for returning said core after each actuation.

3. A shuttle throwing device including an electrically operated shuttle throwing arm, a resilient binder for normally holding the 75 shuttle against movement, and electrically operated magnet for pulling the binder away from the shuttle as the shuttle begins to move.

4. A shuttle throwing mechanism including 80 a pair of solenoids, a core associated with each of said solenoids, an arm connected with each of said cores for engaging and throwing the shuttle along the lay, means for returning said arms and cores 85 after each operation, an electric circuit for each of said solenoids, said electric circuits including a source of power for supplying current to the respective solenoids, a starting switch manually actuated and a pair of 90 contacts acting as an auxiliary switch, means for normally keeping said contacts spaced apart, a cam for actuating one of the contacts for closing the circuit at that point, and means connected with the loom for causing 95 said cam to function at the proper time for throwing the shuttle.

5. In an electrically operated shuttle throwing mechanism, two sets of contacts 100 acting as electric switches, each set including a pair of reciprocable contact pins, springs for normally holding said pins in a given position, which position involves a separation thereof, a cam for successively operating one pin of each set for bringing the pins 105 together, a gear wheel for actuating said cam, and means connected to the loom carrying the shuttle for operating the gear wheel in proper time for causing the shuttles to be thrown at the proper time.

6. A shuttle throwing device including a solenoid, a core adapted to be attracted by the solenoid, a resilient cushion arranged at one end of the solenoid whereby when said core is attracted by the solenoid it will strike 115 said resilient cushion and move the same until the momentum of the core has been checked, an arm connected with said core for actuating a shuttle, and means for returning said core after each actuation.

CLAUDE CHAPMAN FARWELL.
